UNITED STATES PATENT OFFICE.

ALBERT F. W. MEYER, OF CHICAGO, ILLINOIS, ASSIGNOR TO JAMES H. MCGILL, OF VALPARAISO, INDIANA.

SHADE ATTACHMENT FOR ELECTRIC INCANDESCENT LAMPS.

No. 888,521.

Specification of Letters Patent.

Patented May 26, 1908.

Application filed June 6, 1906. Serial No. 320,830.

To all whom it may concern:

Be it known that I, ALBERT F. W. MEYER, a citizen of the United States, residing at Chicago, in the county of Cook and State of Illinois, have invented certain new and useful Improvements in Shade Attachments for Electric Incandescent Lamps, of which the following is a specification.

My invention relates to improvements in shade attachments for electric incandescent lamp fixtures, and has for its salient objects to provide a lamp shade attachment which will be rigid in construction, easy to handle, and which may be connected with any lamp socket and incandescent lamp without the use of tools.

In the practice of my invention I combine, to produce an article of manufacture, a combined socket-and-base shell, having properly connected electric terminals, and having secured thereto, and preferably insulated therefrom, a lamp shade of any suitable style, the device being so constructed that an electric lamp may be screwed into the socket part of the attachment, engaging proper contact parts of the socket member, and the base part of the attachment may be inserted in the customary socket part of an electrical fixture, the contact parts of the base, electrically connected with the like parts of the socket portion of the attachment, completing the electrical connection from the contact parts of the fixture socket to the contact parts of the lamp.

It will be apparent that various constructions may be evolved embodying my invention, and for purposes of full disclosure I have shown in the drawing several different embodiments of my invention.

In said drawing; Figure 1 is a sectional view of my improved lamp attachment. Fig. 2 is a similar view showing a different form of shade and the manner of attachment thereof to the combined base and socket member. Fig. 3 is a like view showing another form of shade and manner of attachment to the base and socket member, and, Fig. 4 is another similar view showing yet a different form of shade and manner of attachment.

Throughout the drawings like numerals of reference refer always to like parts.

In the drawings A represents generally a combined base and socket member, comprising a base portion generally indicated as

a and a socket portion generally indicated as a'. Specifically I prefer that the combined base and socket member be made of a single-piece shell, having a male threaded shell portion 5, adapted to fit in a socket fixture, 60 and a female threaded shell portion 6 adapted to receive an electric incandescent lamp, there being formed at the juncture of the two threads of different diameters a shoulder 8. The portions 5 and 6 of the shell are 65 electrically connected together and constitute the ring contacts of the base and socket parts respectively. Electrically connected center contacts for the base and socket are provided in insulated relation to the ring contacts, a 70 simple and efficient construction being shown in Fig. 1 wherein 9 indicates a plate of insulating material inserted in the hollow socket member and bearing upon the interior shoulder 8 formed at the joint of merger of the two 75 portions of the shell.

10 indicates an insulating plate set in the free end of the base portion of the member and suitably secured therein, as by the upper setting of the metal surrounding it. 80

11 indicates a stem of conducting material extending centrally through the plates 9 and 10 and provided at its opposite end with heads or nuts 12 and 13 respectively arranged at the exterior of the base and the interior end of the socket members and constituting the center contacts of the socket and base respectively.

It will be understood that the construction illustrated, while I consider it to be novel and 90 advantageous, is illustrative only, and I do not desire to be understood as limiting myself to the specific construction described further than as specified in the claims.

To the combined base and socket member 95 I secure in some suitable manner, a lamp shade depending below the socket member to shade a lamp inserted therein. I prefer that the shade be electrically insulated from the base and socket member, and I further 100 prefer that the lamp shade be so secured to said member as to be readily removable therefrom if desired.

In the drawings I have illustrated several constructions embodying my invention and 105 attaining the results described.

In Fig. 1 B indicates a lamp shade of the ordinary flaring type, provided at its upper, smaller end, with an inturned portion b.

14 indicates an interiorly threaded annu- 110

lus adapted to be screw threaded upon the exterior of the socket portions a' of the combined base and socket, and having its under surface cut to conform with the upper extremity and inturned flange of the shade B. 5 15 indicates another ring likewise adapted to be screwed upon the socket portion of the base and socket member and having its upper surface of a shape complementary to that 10 of the lower surface of the ring 14, so that said rings may coact to clamp therebetween the upper portion of the shade. Preferably the ring member 15 is provided with an annular boss 16 which projects through the central opening of the shade and is seated in a corresponding recess in the ring member 14, to insure complete insulation of the shade from the socket member a' . It will be apparent now that when the parts are assembled, as shown in Fig. 1, the shade thereby securely clamped between the rings 14, 15, and by them connected with the combined base and socket member, a lamp C may be screwed into the socket member, and, conveniently using the lamp as a handle for manipulation, the base portion a of the article may be screwed into the customary socket of an ordinary lamp fixture, electrical connection between the ring contact of the fixture 20 socket and the ring contact of the lamp being afforded through the electrically connected shell portions 5 and 6 of the combined socket and base, and connection from the center contact of the fixture socket to the center 25 contact of the lamp being afforded through the contact pieces 12, 13 and their connecting stem 11.

In Fig. 2 I have shown a construction embodying my invention wherein B' is a shade 40 provided at its top with a flaring portion b'. To accommodate such construction the rings 14^a and 15^a have their respective lower and upper surfaces shaped for coaction with the upper portion of the shade, to clamp the same therebetween. If desired ventilating 45 apertures 17—17 may be formed in the rings 14^a and 15^a to permit the escape of the heat generated by the lamp.

In Fig. 3 I have shown a construction generally similar to that shown in Fig. 1, save that the ring members 14^b and 15^b grasp between them an annular supporting plate 18, provided with ventilating apertures 18^b and having a down-turned rim 19 through which 55 project suitable set screws 20 arranged to take under the flaring edge b² of a suitable shade B^b.

In Fig. 4 I have shown a well known form of shade B^c having a substantially flat top 60 portion b^c secured directly between the clamping rings 14^c and 15^c.

I have shown these modifications as suggestive to those skilled in the art, of the adaptation of my invention to various well known forms of shades, but it will be apparent to those skilled in the art that it may be readily adapted to yet other forms of shades, and I do not desire to be understood as limiting the scope of my invention to the specific embodiments shown.

Having thus described my invention, what I claim and desire to secure by Letters Patent, of the United States is:

1. The combination of a single piece sheet metal conductive shell having a lower part 75 constituting a socket, spirally corrugated to constitute a thread both inside and outside, and an exteriorly threaded upper part of smaller diameter constituting a base; a shade, and means for supporting the shade 80 in insulated relation to the shell comprising a pair of opposing, interiorly threaded rings engaging the exterior thread of the socket and constituting opposing members of a clamp.

2. The combination of a single piece sheet metal conductive shell having a lower part 85 constituting a socket, spirally corrugated to constitute a thread both inside and outside, and an exteriorly threaded upper portion of different diameter constituting a base, a 90 shade, and means for attaching said shade to the shell, comprising two insulating rings screwed onto the exterior thread of the socket, gripping therebetween the shade and arranged to prevent contact of the shade 95 with the shell.

3. The combination of a conductive sheet metal shell having a lower part constituting a socket spirally corrugated to constitute a 100 thread both inside and outside, and an exteriorly threaded upper portion constituting a base, and two insulating rings, both threaded onto the exterior of the socket, each tapering toward one side and arranged with their smaller sides confronting, and a lamp shade, 105 secured between said tapering surfaces of the rings.

4. The combination of a combined sheet-metal base and socket shell corrugated to provide an exterior and interior thread, a 110 lamp shade, and means for securing the lamp shade to the socket comprising two insulating rings each screwed on to the outside screw thread of the socket and clamping the shade therebetween.

In testimony whereof I hereunto set my hand in the presence of two witnesses.

ALBERT F. W. MEYER
